UNITED STATES PATENT OFFICE

HORACE LEOPOLD TUCKER BUCKLE, OF IVER HEATH, ENGLAND, ASSIGNOR TO VICTOR
TALKING MACHINE COMPANY, OF CAMDEN, NEW JERSEY, A CORPORATION OF NEW
JERSEY

TALKING MACHINE

Application filed July 28, 1925, Serial No. 46,648, and in Great Britain September 4, 1924.

This invention relates to improvements in talking machines of the type embodying a sound reproducer in the form of a large diaphragm carried at the end of a member 5 capable of swinging across the record, and in particular to an improved method of mounting the diaphragm so that it will play in a position inclined or at right angles to the plane of the record and when not in use 10 can be folded down to lie approximately parallel with the record.

The principal object of the invention is to provide means whereby when the diaphragm is folded down into the horizontal 15 position its lower edge, at which the stylus bar is pivoted, is moved forward, or advanced in front of the position which it occupies during playing, with the consequence that the whole of the diaphragm when lowered can 20 be brought into the space available in a talking machine cabinet constructed for the ordinary sound arm machine of to-day even though the diameter of the large diaphragm is greater than the distance from the sound 25 arm pivot of the ordinary machine to the turntable centre. In the ordinary machine of to-day the sound arm is pivoted as a rule quite close to the back of the cabinet and the new attachment may be fixed in precisely the 30 same position as at present occupied by the pivoted sound arm.

According to the invention therefore, a talking machine of the type referred to above is provided in which when the diaphragm is 35 moved on the swinging supporting member from its playing position to a non-playing position substantially parallel with the record, the diaphragm is also moved bodily in a direction away from the axis of rotation 40 of the swinging member and towards the side of the machine remote from the said axis of rotation.

In the preferred construction, the diaphragm is mounted to rotate about a horizontal axis carried by a member which is 45 itself carried on the swinging member in such a manner as to be capable of rotation about a horizontal axis, the movements of the diaphragm about these two horizontal axes taking place simultaneously and under the con-

trol of a rod pivotally connected at or near the edge of the diaphragm and sliding in friction bearings in the swinging member and in a direction substantially parallel to the longitudinal axis thereof.

The invention is illustrated by way of example in the accompanying drawings in which

Fig. 1 is a side elevation of the apparatus 60 the parts being shown in the playing position.

Fig. 2 is a similar view to Fig. 1 with the parts in the non-playing position.

Fig. 3 is a plan view of the diaphragm carrying means the diaphragm itself being 65 omitted for the sake of clearness and

Fig. 4 is a rear elevation of a part of the diaphragm showing the method of connection to the carrying means.

Referring to the drawings, 1 is a member 70 adapted to rotate about a vertical axis determined by bearings formed in a member 2 screwed to the motor board 3. The member 1 is furnished with a short upwardly extending arm 4 having a wide outer end 5. This wide end 5 extends between a pair of lugs 6 formed on the end of a long member 7 adapted to swing across the record 8 as the part 1 rotates in its bearings.

The connection of lugs 6 and wide end 5 is 80 effected by passing a pin 9 through holes formed therein and securing it by nuts 10 at the ends so that member 7 is capable of being swung upwards about pin 9. A spring buffer 11 is provided beneath the member 7, said 85 buffer comprising a spring pressed plunger 12 moving in a casing 19 and engaging with a stud 13 on the under side of the arm 4 so that only a portion of the weight of the parts pivoted on the pin 9 rests on the record. At 90 the outer end of the arm 7 are formed lugs 14 between which is pivoted one side 15 of a plate 16, the connection being by means of screws 17 passed through the lugs 14 and into thickened parts of the plate 15. The other side 20 of the plate 16 carries lugs 21 (Fig. 3) to which the diaphragm 22 is pivotally connected by means of screws 23 passed through apertures in brackets 24 secured to the diaphragm holding ring, Figs. 1 and 2. 100

In the construction illustrated the diaphragm plays in a position at right angles to the record and when in this position the plate 16 slopes upwardly at an obtuse angle from the member 7 towards the diaphragm.

The line through screws 23 about which the diaphragm pivots is at a short distance above the lower edge of the diaphragm, and pivotally connected at a point below this line to the holding ring, or preferably to the block 25 which carries the stylus holder 26 and is itself connected to the holding ring, is a small bracket 27 to which is attached a rod 28 adapted to slide smoothly in friction bearings 29, 30, mounted on the member 7. When the diaphragm is raised into the playing position the bracket 27 forms a stop limiting the rearward movement of the rod 28, the block 25 engaging with the inner face 27' of bracket 27 and thereby determining the fully raised position of the diaphragm. When the diaphragm is folded down parallel with the record the rod 28 is drawn forward in its friction bearings 29 and 30, the bracket 27 pivots on the block 25, and the diaphragm and plate 16 at the same time move about the bearings 23 and 17, the plate 16 gradually assuming an almost horizontal position as shown in Fig. 2.

The position of axis 17—17 being fixed with regard to the member 7 the axis 23—23 is moved through an arc of a circle and when the diaphragm is turned down occupies a position corresponding to the point shown in Fig. 2 which is at a greater distance from the axis of rotation of member 7 than when in the position shown in Fig. 1. The diaphragm 22 is therefore moved bodily to the right in Figs. 1 and 2 and the top 31 of the diaphragm in the lowered position does not project to the left beyond the member 2.

The bearings for the rod 28 are in the form of sleeves 32 and 33 mounted in the member 7 and within which are provided felt packings 34 to ensure smooth movement of the rod. Between the sleeves 32, 33 is a recess in which rests the spider 35 of the diaphragm when in the lowered position. In the underside of the rod 28 is formed a notch 36 which when the diaphragm is in the raised position engages with a bent spring 37, so that the diaphragm can only be moved from the vertical position by the exertion of a certain force.

I claim:

1. A talking machine comprising a rotatable record support, a sound reproducer adapted to move across said support and to lie in a different plane when playing from that which it occupies when not in use, and means for carrying said sound reproducer including an arm adapted to swing about a vertical axis in a plane substantially parallel with the record support, means pivotally connecting said arm and reproducer and a

link member pivotally connected to said arm and to the sound reproducer independently of said second named means and adapted to move the sound reproducer bodily away from the axis of rotation of the swinging arm and towards the side of the machine remote from said axis when the sound reproducer is moved from its playing to the non-playing position.

2. A talking machine comprising a rotatable record support, a sound reproducer adapted to move across said support and to lie in a plane substantially at right angles to said support when playing and in a plane substantially parallel to the record support when not in use and means for carrying said sound reproducer including an arm adapted to swing about a vertical axis in a plane substantially parallel with the record support, a member slidably carried by the arm and pivotally connected to the diaphragm and a link member pivotally connected to said arm and to the sound reproducer and adapted to move the sound reproducer bodily away from the axis of rotation of the swinging arm and towards the side of the machine remote from said axis when the sound reproducer is moved from its playing to the non-playing position.

3. A talking machine comprising a rotatable record support, a sound reproducer adapted to move across said support and to lie in a different plane when playing from that which it occupies when not in use and means for carrying said sound reproducer including an arm adapted to swing about a vertical axis in a plane substantially parallel with the record support, means pivotally connecting said reproducer and arm and a link member upon which the sound reproducer is mounted to rock about a horizontal axis and which is itself adapted to rock about a horizontal axis upon the swinging arm and to move the sound reproducer bodily away from the vertical axis of rotation of the swinging arm and towards the side of the machine remote from said axis when the sound reproducer is moved from its playing to the non-playing position.

4. A talking machine comprising a rotatable record support, a sound reproducer adapted to move across said support and to lie in a different plane when playing from that which it occupies when not in use, means for carrying said sound reproducer including an arm adapted to swing about a vertical axis in a plane substantially parallel with the record support, a link member upon which the sound reproducer is mounted to rock about a horizontal axis and which is itself adapted to rock about a horizontal axis upon the swinging arm and to move the sound reproducer bodily away from the axis of rotation of the swinging arm and towards the side of the machine remote from said axis when the sound reproducer is moved from its playing to the non-playing position, and means

5 operatively connected to said diaphragm and arm to control the simultaneous movements of the sound reproducer and link member about said horizontal axes, said last named means being mounted independently of said link.

10 5. A talking machine comprising a rotatable record support, a sound reproducer adapted to move across said support and to lie in a different plane when playing from that which is occupies when not in use, means for carrying said sound reproducer including an arm adapted to swing in a plane substantially parallel with the record support and a link member upon which the sound reproducer is mounted to rock about a horizontal axis and which is itself adapted to rock about a horizontal axis upon the swinging arm and to move the sound reproducer bodily away from the axis of rotation of the swinging arm and towards the side of the machine remote from said axis when the sound reproducer is moved from its playing to the non-playing position, and a rod pivotally connected to the sound reproducer, and slidably on the swinging arm to control the simultaneous movements of the sound reproducer and link member about their horizontal axes.

15 6. A talking machine comprising a rotatable record support, a sound reproducer adapted to move across said support and to lie in a different plane when playing from that which it occupies when not in use, means for carrying said sound reproducer including an arm adapted to swing in a plane substantially parallel with the record support and a link member upon which the sound reproducer is mounted to rock about a horizontal axis and which is itself adapted to rock about a horizontal axis upon the swinging arm and to move the sound reproducer bodily away from the axis of rotation of the swinging arm and towards the side of the machine remote from said axis when the sound reproducer is moved from its playing to the non-playing position, a sliding rod, a bracket on said rod, a block on the sound reproducer to which the rod is connected through the medium of the bracket, said bracket being adapted to engage the block to limit the movement of the sound reproducer and link member about their horizontal axes into the playing position.

20 7. A talking machine comprising a rotatable record support, a sound reproducer adapted to move across said support and to lie in a different plane when playing from that which it occupies when not in use, means for carrying said sound reproducer including an arm adapted to swing in a plane substantially parallel with the record support and a link member upon which the sound reproducer is mounted to rock about a horizontal axis and which is itself adapted to rock about a horizontal axis upon the swinging arm and to

move the sound reproducer bodily away from the axis of rotation of the swinging arm and towards the side of the machine remote from said axis when the sound reproducer is moved from the playing to the non-playing position, 70 friction bearings carried by said swinging arm, and a rod pivotally connected to the sound reproducer, said rod being adapted to slide in said friction bearings to control the simultaneous movements of the sound reproducer and link member about their horizontal axes and locking means for said sliding rod to maintain the sound reproducer in the playing position.

75 8. A mounting of the class described comprising, in combination with a large sized diaphragm, an arm adapted to swing in a horizontal plane, and a pair of members carried by said arm and pivotally connected to said diaphragm adjacent the edge thereof, 80 one of said members being longitudinally movable with respect to said arm.

90 9. A mounting of the class described comprising, in combination with a large sized diaphragm, an arm mounted to swing about a vertical axis, a link pivoted to said arm and diaphragm, and means longitudinally movable with respect to said arm and carried thereby for yieldingly maintaining said diaphragm in an upright playing position, said 95 last named means being pivoted to the diaphragm.

100 10. A mounting of the class described comprising, in combination with a large sized diaphragm, a spider for mounting said diaphragm, an arm adapted to swing about a vertically disposed axis, said arm being provided with a recess to receive said spider when the diaphragm is moved to non-playing position, and means for yieldingly holding said diaphragm and spider in a substantially upright playing position, said means including a link pivotally secured to said spider and arm, and a rod slidably carried by said arm and pivoted to said spider below the pivotal connection for said link.

105 11. A mounting of the class described comprising a horizontally swinging arm provided with bearing members, a rod longitudinally movable in said bearing members, a link pivoted to said arm, and a large sized diaphragm pivoted to said link and rod, said diaphragm being adapted to occupy a substantially vertical playing position and a substantially horizontal non-playing position.

115 12. A mounting for a large sized diaphragm which is adapted to occupy a substantially upright playing position and a substantially horizontal non-playing position comprising an arm adapted to swing about a vertical axis, means pivotally connecting said diaphragm and arm, and means slidably carried by said arm and pivoted to said diaphragm, the pivots for said first and second means being so positioned that move-

ment of the diaphragm from playing to non-playing position results in bodily movement of the diaphragm away from said vertical axis.

5 13. A mounting of the class described comprising, in combination with a large sized diaphragm, an arm mounted to swing about a vertical axis, a link pivoted to said arm and diaphragm, and means slidably carried by
10 said arm and pivoted to said diaphragm below the pivotal connection of said link thereto.

14. A mounting of the class described comprising, in combination with a large sized
15 diaphragm, a horizontally swinging arm provided with bearing members, a link pivoted to said arm and to said diaphragm, and a rod longitudinally movable in said bearing members and pivoted to said diaphragm below the pivotal connection of said link thereto.

15. A mounting of the class described comprising, in combination with a diaphragm, a spider for mounting said diaphragm, stylus holding means mounted on said spider, an
25 arm adapted to swing about a vertically disposed axis, said arm being provided with a recess to receive said spider when the diaphragm is moved to non-playing position,
30 and means for holding said diaphragm and spider in a substantially upright playing position, said means including a link pivotally secured to said spider and arm, and a rod slidably carried by said arm and pivoted to
35 said stylus holding means.

In testimony whereof I have signed my name to this specification.

HORACE LEOPOLD TUCKER BUCKLE.
